UNITED STATES PATENT OFFICE.

LUDWIG F. MEYER, OF CLEVELAND, OHIO.

WRENCH.

1,405,795.

Specification of Letters Patent.

Patented Feb. 7, 1922.

Application filed September 8, 1921. Serial No. 499,151.

To all whom it may concern:

Be it known that I, LUDWIG F. MEYER, a citizen of the United States, residing at Cleveland, in the county of Cuyahoga and

5 State of Ohio, have invented certain new and useful Improvements in Wrenches, of which the following is a specification.

This invention relates to wrenches of that type in which the head is clutched by a 10 handle when the latter is turned one way, and is released when the handle is turned the other way, and is especially an improvement on the wrench shown in the patent to Ludwig F. Meyer #1161064. In said patent a head is provided with a set of grooves 15 on the outside thereof, and these grooves are engaged by ribs on a set of wedges which are operated by an oscillating handle. It has been found that by forming the 20 grooves in the collar instead of the head, with the ribs on the outer side of the wedges instead of on the inner side, and providing shoulders on the head instead of on the collar, the tool is made more positive in operation and is generally superior in action 25 and construction.

A wrench provided with these improvements is illustrated in the accompanying drawings in which Fig. 1 is a plan of the 30 wrench. Fig. 2 is a longitudinal section. Figs. 3 and 4 are top and side views of the head. Fig. 5 is a perspective of one of the wedges.

Referring specifically to the drawings, 6 35 indicates a handle which is integral or rigid with a collar 7, the inner face of which is provided with a series of circular ribs 8, with intervening grooves, V-shaped in section. In this collar fits loosely a head 9 40 having sockets 10 to receive a nut or the like. This head is circular, and its periphery is provided with a series of inclines 11 forming shoulders 12 at the ends of the inclines. A corresponding series of wedges 45 13 fit between the inclined surfaces 11 and the collar 7, and these wedges are provided on the outer side with ribs 13^a and intervening grooves corresponding to the ribs 8. The wedges are curved to segmental form 50 and have a rather slight taper, and in operation the wide ends of the wedges back or stop against the shoulders 12 when the handle is shifted to release position. The clearance between the ribs and grooves of 55 the head and collar is quite small; just suffi-

cient to open on the back throw, and the clutching action results from the friction when the handle is swung in the proper direction.

In operation, on the power stroke, the 60 wedges are picked up by the friction between the same and the ribs on the collar, and are caused to ride up the inclines 11, thereby forming a wedge clutch between the head and the handle. On reverse operation 65 of the handle, the wedges slip down or back along the inclines, and the head is released, permitting the handle to be turned back for a fresh grip. The wrench can therefore be operated in confined spaces, and a very small 70 movement of the handle will produce a grip or release, and hence the nut can be adjusted to a fine position. As stated, it has been found by test that a wrench constructed as above described will give a quicker and 75 more positive action than the patented wrench above referred to.

Although shown in connection with a wrench the same construction or principle of operation may be applied to various other 80 types of machines or devices where an automatic clutch and release is employed, to connect an oscillating lever or the like to a head which is rotated intermittently.

I claim:

1. A wrench comprising a collar provided with a handle, the inside of the collar having a series of annular ribs, a series of wedges within the collar having grooves receiving said ribs, and a cylindrical head 90 having external inclines against which the inner surface of the wedges rest.

2. A wrench comprising a handle and a collar, the latter having a series of annular V-shaped ribs extending around the inside thereof, a cylindrical head extending through the collar and spaced therefrom, the head having a series of external inclines and shoulders at the ends of said inclines, and a series of wedges fitting between the head 95 and the collar, the inner sides of the wedges resting against the inclines and the outer sides of the wedges having a series of grooves receiving said ribs.

In testimony whereof, I affix my signature 105 in presence of two witnesses.

LUDWIG F. MEYER.

Witnesses:

JOHN A. BOMMHARDT,
BESSIE F. POLLAK.
